HAIR CURLER ATTACHMENT

Carole A. Lennon, Sylmar, Calif., assignor to Tarnreed
Limited, London, England
Filed May 6, 1968, Ser. No. 11,783

Term of patent 14 years

Int. Cl. D28—03

U.S. Cl. D86—10

Fig. 1

Fig. 2

Fig. 4

FIG. 1 is a perspective front view of a hair curler attachment showing my new design, the broken line showing of a flatiron and a curler is for purposes of illustration only;

FIG. 2 is a rear elevational view of the design shown in FIG. 1;

FIG. 3 is a side elevational view thereof; and

FIG. 4 is a front elevational view.

I claim:

The ornamental design for a hair curler attachment, substantially as shown and described.
